UNITED STATES PATENT OFFICE.

EDMUND ORR DEMING, OF SAN FRANCISCO, CALIFORNIA.

DEVICE FOR DISENGAGING SCALE-BEAM LATCHES.

SPECIFICATION forming part of Letters Patent No. 365,170, dated June 21, 1887.

Application filed January 24, 1887. Serial No. 225,382. (No model.)

To all whom it may concern:

Be it known that I, EDMUND ORR DEMING, of the city and county of San Francisco, State of California, have invented an Improvement 5 in Scale Attachments; and I hereby declare the following to be a full, clear, and exact description of the same.

My invention relates to an attachment for weighing-scales; and it consists of a device by 10 means of which the stop or latch holding the scale-beam from vibration may be disengaged without the use of hands.

Referring to the accompanying drawings for a more complete explanation of my invention, 15 Figure 1 represents weighing-scales having my attachment. Fig. 2 is a modification.

In platform weighing-scales the scale-beam is prevented from vibration or oscillation by a swinging stop or latch journaled above its 20 outer end, and this is usually provided with a short lever upon one side, by which the operator disengages it to allow the beam to move after the load has been placed upon the scale. This, however, is troublesome in many cases 25 where the operator may have book and pencil in hand for the purpose of tallying the weights, and my invention is designed to obviate this difficulty.

A is the vertical post, and B the horizontal 30 arm, of an ordinary platform-scale. C is the latch or stop which prevents the oscillation of the scale-beam D. Upon the outer end of the shaft of this stop is fixed a lever, E, the arms of which project in opposite directions from 35 the central shaft, as shown. From the lower arm a cord, F, passes over a pulley, G, which is fixed at the inner end of the horizontal arm B, or upon the side of the vertical post, and from this pulley the cord passes downward 40 along the back of the post, and is connected with a slide, H, near the bottom. This slide has a projection, upon which the foot may be placed to push it down, and this operates through the cord and turns the lever, and with 45 it the stop, thus freeing the scale-beam and

allowing it to be used for weighing. From the opposite end of the lever E a spring, I, extends to the side of the horizontal arm B, to which it is attached, and this spring serves to return the stop to its position when the cord is released by raising the foot.

A coil-spring might be made to surround the stop-shaft, or it might be returned in any suitable way, and in place of the slide H, to which the cord is attached, a foot-lever might 55 be employed; but these are essentially mechanical changes which will suggest themselves to any one, and may be made to suit such changes as are necessary to scales in various positions. The connection between the 60 foot-piece and the latch or stop may also be made by means of rigid rods in place of a cord, and quadrants or bell-crank levers may be used to change direction at the intervening angles, as seen in Fig. 2, instead of pulleys. 65

Having thus described my invention, what I claim as new, and desire to secure by Letters Patent, is—

1. In combination with the scale-beam, a stop by which it is prevented from oscillating, 70 a lever, a cord, and a foot-piece whereby the stop may be withdrawn to release the beam, substantially as herein described.

2. The stop by which the scale-beam is prevented from oscillating, in combination with 75 a lever, a cord, and a foot-piece by which it is withdrawn, and a return-spring, substantially as herein described.

3. A stop by which a scale-beam is prevented from oscillating, in combination with a movable foot-piece and intermediate rods or cord, and a pulley or a bell-crank lever by which a change of direction is effected, substantially as 80 herein described.

In witness whereof I have hereunto set my 85 hand.

EDMUND ORR DEMING.
